MARYLAND.

DRAFT RIGGING.

Application filed March 30, 1922. Serial No. 548,199.

To all whom it may concern:

Be it known that we, BYERS W. KADEL and PERCY R. DRENNING, citizens of the United States, residing at Baltimore city, in the State of Maryland, have invented certain new and useful Improvements in Draft Rigging; and we do hereby declare the following to be a full, clear, and exact description of the invention, such as will enable others skilled in the art to which it appertains to make and use the same.

This invention relates to draft rigging for railway cars and, generally stated, consists in providing a vertical key connection between the coupler and a horizontal yoke.

The present invention has for an object to provide in combination, a vertical key connection adapted to permit relative movement between the yoke and coupler, means for supporting and guiding said key, said means also serving to support the forward end of the yoke, and means for limiting the forward movement of the coupler key and yoke beyond a predetermined position, said last named means being connected to the center sills of the draft rigging.

Another object of the invention consists in the provision of upper and lower vertical key guide members connected to the center sills, said members being provided with means arranged to guide and support the forward end of the yoke.

A further object of the invention is to provide a draft rigging so constructed and arranged as to transmit excessive loads to the car underframe without detriment to the latter, said draft rigging including a vertical key connection between the coupler and yoke, means for limiting the forward movement of said key and yoke beyond a predetermined position, said means comprising a combined striking casting and carry iron connected to the draft sills, and a backstop member for limiting the rearward movement of the yoke beyond a predetermined position.

Other objects will be obvious, as herein-after set forth, reference being had to the accompanying drawings in which—

Figure 1 is a sectional plan view of the

center sills and associated parts of a car underframe showing a draft rigging constructed in accordance with the present invention.

Figure 2 is a central longitudinal vertical sectional view of the construction shown in Figure 1, parts of the mechanism being illustrated in side elevation.

Figure 3 is a fragmentary horizontal sectional view of the forward portion of the draft rigging embodying the invention.

Figure 4 is a transverse vertical sectional view on the line 4—4 of Figure 2.

Figure 5 is a similar view illustrating a slightly different form of upper guide member.

The center or draft sills are indicated at 1—1 and the backstop casting at 2, said casting being connected to the sills by means of rivets 3. Each sill is provided with a longitudinally extending slot 4 and to the outer face of each sill is connected a cheek plate 5. Each cheek plate is formed with a slot 6 and may be provided with a boss 7 adapted to surround the edges of the slot 5 and extend through the slots 4 in the center sills. Rivets 8 firmly connect the cheek plates to the oppositely disposed center sills.

Located between the sills is the horizontal yoke 9 provided at its forward end with the hooded head 10, the top and bottom walls of which are provided with longitudinally extending key receiving slots 11. These slots 11 have their forward opposed side faces inclined and extending laterally into the relatively wide portions providing parallel opposed faces, as shown in Figure 1, thereby providing lateral clearance for the pivotal movement of the coupler key, the key slot in the coupler being adapted to closely embrace said key. The forward portions of the upper and lower arms of the yoke are forwardly inclined and the slots 11 are preferably enlarged for increased bearing at these points for the vertical coupler key 12. The enlarged portions extend laterally and toward the side walls of the yoke head 10, the inclined portions 13 forming shoulders on the top and bottom walls of the yoke adapt-

ed to cooperate with guide means provided on the upper and lower key retaining members to be hereinafter described.

Within the yoke arms and bearing at its forward end against the key connected follower 14 and the inner face of the rear wall of the yoke, is the cushioning mechanism 15 which is only diagrammatically illustrated by the dot and dash lines in Figures 1 and 2. The follower 14 is provided with a slot 16 through which extends a key 17, said key in normal position of the gear engaging the rear wall of the slot 16 in the follower and engaging at its forward edges against the forward ends of the slots 6 in the check plates 4 through which said key extends. The vertical coupler key 12 is arranged to slidably connect the coupler to the yoke 9, the said key in the normal position of the gear engaging the rear wall of the slot in the coupler, and engaging at its forward edges against the forward end of the slots 11 in the yoke head. The key 12 is of a length which provides for its extending above and below the upper and lower faces of the yoke arms, said key being of a length greater than the combined thickness of the yoke and coupler. The projecting portions of the coupler key are adapted to be guided and supported in the manner to be now described.

The means for guiding and retaining the vertical key 12 comprises a lower member or plate 18 having flanges 19 connected by means of bolts 20 to the lower flanges of the draft sills. The member 18 is formed with upwardly projecting portions 21 forming supporting bearing surfaces 22 for the yoke, and a centrally depressed portion 23, the said depressed portion forming a support and bearing face for the coupler key, as clearly shown in Figure 4. A sufficient height is given to the upwardly projecting portions 21 so that the yoke will be maintained in its normally horizontal plane. The depressed portion of the plate 18 is sufficiently low to provide for the lower end of the vertical coupler key effectively engaging a lower front stop on the carry iron, which latter is to be presently described. The inner opposed faces of the upwardly projecting portions 21 are spaced sufficiently from the shoulders formed by the inclined walls 13 on the yoke arms, and as shown, said inner opposed faces are slightly inclined, thereby providing ample clearance for the swinging of the yoke upon the supporting and bearing surfaces 22. A longitudinal bearing surface is provided on the depressed portion of the lower member 18, the vertical key 12 being movable on said bearing surface which, as shown in Figure 2, is uninterrupted at each end. From the foregoing construction it will be obvious that a relatively light but corre-

spondingly strong key retaining and yoke guiding member has been provided, the upwardly projecting portions 21 and the depressed portion 23 of the member constituting substantially a corrugated construction. 70

The upper member or plate 24 is connected to the upper flanges of the center sills by means of rivets 25. The plate 24 is slightly arched, and the uppermost end of the vertical key 12 is spaced therefrom, as shown. Each end of the plate member 24 is uninterrupted in a manner similar to the lower member 18, the forward supplemental stops for the vertical key being provided on the combined striking casting and carry iron 26 now to be described. 75

This combined member 26 includes the striking casting 27 and the carry iron 28, both of said parts being connected by depending sections 29 firmly connected to the inner faces of the draft sills by means of rivets 30. Flanges 31 project laterally from the striking casting, said flanges extending outwardly over the top flanges of the draft sills, and being connected thereto by means of rivets 32. The combined member 26 constitutes a box-like casting, the striking and carry iron portions bridging the integral depending sections 29 at both top and bottom, respectively, of the draft sills. 90

A supplemental front stop 33 is provided on the striking casting 27, and a similar stop 34 is formed in the carry iron support 28. These respective stops are preferably direct portions of the said striking casting and carry iron support, both of said stops being vertically aligned and adapted to be engaged by the forward top and bottom edges of the vertical coupler key, when the cushioning mechanism becomes solid. An open slot or depression 35 formed in the rear edge of the striking casting terminates in the curved stop portion 36, the flaring side faces of the slot permitting relative clearance for the key when entering and moving within said slot upon engagement with the stop portion thereof. The rear edge of the striking casting is located in close proximity to the front edge of the top key retaining member 24, the slot in the striking casting forming a guide means for the vertical key immediately adjacent said top member 24. 100

In the rear edge of the carry iron support 28 is formed a similar open slot or depression 37, said depression having a forward curved stop portion with which latter the front edge of the lower end of the vertical key engages. The depression 37 forms a partial guide means for the lower end of the key, the lower supporting member 18 for said key extending well forward and in substantially close proximity to the depression in the rear edge of the carry iron, as shown in Figure 2, thereby preventing the 110

dropping or dislodgment of the key, as will be understood. The rear face of the member 26 contiguous to the respective depressions 35 and 37, are inclined forwardly, as shown in Figure 2, forming seats for the reception of the respective inclined portions on the front of the yoke arms. These respective inclined portions engage when the cushioning mechanism becomes solid, and form direct points of contact for transmitting excessive strains to the draft sills.

From the foregoing construction it will be seen that there is provided a unitary or one-piece casting and carry iron member 15 having front stops formed therewith and adapted to prevent movement of the vertical coupler key in a forward direction beyond a predetermined position. It will be seen that when the cushioning mechanism becomes 20 solid, that is, at the limit of movement of the cushioning mechanism, the front, top and bottom edges of the coupler key engage the stop portions of the depressions in the rear edges of the combined striking and carry iron member, and at the same time the inclined portions of the yoke engage the inclined seats adjacent said depressions, thereby preventing further forward movement of said key and yoke, and, in turn 25 transmitting the excessive strains incident to the increased load transmitted to the draft sills. On draft it will be seen that the excessive loads are taken at a plurality of points, namely, the forward ends of the slots 30 6 through the horizontal key 17, the supplemental vertical key stops formed in the depressions 35 and 37, and the coacting inclined portions of the yoke head and the member 26. On buffing movement the 35 strains are also received at a plurality of points, namely, the rear end of the slots 6 in the cheek plates, and the buffing face of the backstop member 2.

In Figure 5 I have shown a modified 40 form of construction in which both upper and lower key and yoke guiding members are of similar shape. The lower member 38 is attached to the lower flanges of the draft sills, as shown, and is provided with the 45 elevated yoke, supporting portions 39, and the central depressed portion 40, by means of which both the yoke and vertical key are supported and guided, as hereinbefore described. The upper member 41 is connected to the top flanges of the center sills by means of rivets 42, and has formed therewith depending sections 43 having bearing surfaces 44 slightly spaced from the top of the yoke head, as clearly shown in 50 Figure 5. An upwardly projecting center portion 45 is provided in the top member 41, said center portion having inclined opposed walls 46 which serve to co-act with the outer edges of the inclined walls 12 provided on the enlarged portions of the

yoke head, said inclined opposed walls 46 serving to guide the yoke head in a manner similar to that hereinbefore described in connection with the lower yoke support and key retaining member 18. The center portion 45 70 of the member 40 is projected upwardly sufficiently far to extend slightly above the upper end of the vertical key, the aforesaid inclined opposed walls 46 converging at their upper ends to act as a guide for said key. 75

By this construction the front end or head of the horizontal yoke is effectively supported, guided and always maintained in operative relation to the other associated parts of the draft rigging, the present construction also acting to guide and retain the vertical coupler key used in connection with said horizontal yoke. 80

We claim:—

1. In a draft rigging, the combination 85 with spaced draft sills, of a coupler and a yoke, means connecting said yoke and coupler comprising an upright key, means connected to the forward end of the draft sills adapted to be engaged by the said key 90 and yoke for limiting the forward movements thereof beyond a predetermined position, and means adapted to prevent movement of said yoke in a rearward direction beyond a predetermined position. 95

2. In a draft rigging, the combination with spaced draft sills, of a coupler and a yoke, an upright key connecting said yoke and coupler, a member connected to said draft sills and adapted to close the forward end of the draft rigging recess, said member acting to limit the forward movement of the said connecting key beyond a predetermined position, and means connected to said draft sills and adapted to prevent rearward movement of said yoke beyond a predetermined position. 105

3. In a draft rigging, the combination 110 with draft sills, of cushioning mechanism, a coupler and horizontal yoke, a vertical coupler key operably connecting said coupler and yoke for permitting relative movement therebetween, means located at the front of said draft sills and adapted to be engaged by said key for limiting the forward movement thereof beyond a predetermined position, and means at the rear of said horizontal yoke for preventing rearward movement thereof beyond a predetermined position. 115

4. In a draft rigging, the combination 120 with draft sills, of cushioning mechanism, a coupler and a yoke, means connecting said coupler and yoke adapted to permit relative movement therebetween, and means for limiting the forward and rearward movements of said yoke beyond predetermined positions, said means including stop members connected to the draft sills adjacent the rear end of said coupler and adapted to be engaged by adjacent portions of the yoke 125 130

when the cushioning mechanism becomes solid for transmitting excessive loads to said draft sills.

5. In a draft rigging, the combination with center sills, of cushioning mechanism, a coupler and horizontal yoke, a vertical coupler key connecting said coupler and yoke adapted to permit relative movement therebetween, and means including a plurality of stop members connected to said center sills for preventing forward or rearward movement of said horizontal yoke beyond predetermined positions, said yoke having adjacent its forward ends portions adapted to engage one of the stop members.

6. In a draft rigging, the combination with draft sills, of cushioning mechanism, a coupler and a yoke, means connecting said coupler and yoke and adapted to permit relative movement therebetween, a stop at the front end of said draft sills adapted to be engaged by said yoke for limiting the forward movement thereof, and means at the rear of said yoke connected to said draft sills for limiting the rearward movement of said yoke.

7. In a draft rigging, the combination with draft sills, of a coupler, a horizontal yoke and cushioning mechanism, means including a vertical key for connecting the yoke and coupler, said means being adapted to permit relative movement therebetween, means adapted to prevent rearward movement of the yoke beyond a predetermined position, and a member connected to the forward end of the draft sills and against which said vertical key engages when the cushioning mechanism becomes solid, said members being adapted to be engaged by the yoke.

8. In a draft rigging, the combination with draft sills, of a coupler, a horizontal yoke and cushioning mechanism, means including a vertical key for connecting the yoke and coupler, said means being adapted to permit relative movement therebetween, means adapted to prevent rearward movement of the yoke beyond a predetermined position, and a member connected to the forward end of said draft sills, said member having vertically aligned rear edges forming front stops for the upper and lower ends of said vertical key.

9. In a draft rigging, the combination with draft sills, of a coupler, a horizontal yoke and cushioning mechanism, means including a vertical key for connecting the yoke and coupler, said means being adapted to permit relative movement therebetween, means adapted to prevent rearward movement of the yoke beyond a predetermined position, and a one-piece casting connected to the forward end of said draft sills, said casting having a rear face against which the

front edge of the vertical coupler key engages when the cushioning mechanism becomes solid.

10. In a draft rigging, the combination with draft sills, of a coupler, a horizontal yoke and cushioning mechanism, means including a vertical key for connecting the yoke and coupler, said means being adapted to permit relative movement therebetween, means adapted to prevent rearward movement of the yoke beyond a predetermined position, and a combined striking casting and carry iron support connected to said draft sills and adapted to form a front stop for the vertical coupler key upon movement of said key in a forward direction beyond a predetermined position.

11. In a draft rigging, the combination with draft sills, of a coupler, a horizontal yoke and cushioning mechanism, means including a vertical key for connecting the yoke and coupler, said means being adapted to permit relative movement therebetween, means adapted to prevent rearward movement of the yoke beyond a predetermined position, and a combined striking casting and carry iron support having depressed portions in the rear face thereof, said depressed portions forming guide recesses and front stops for said vertical coupler key.

12. In a draft rigging, the combination with draft sills, of a coupler, a horizontal yoke, a vertical key connecting said yoke and coupler adapted to permit relative movement therebetween, means connected to the draft sills for supporting and guiding said vertical key, and a unitary member connected to the forward end of said draft sills and adapted to form co-acting guide and stop means for said vertical coupler key upon forward movement thereof beyond a predetermined position.

13. In a draft rigging, the combination with draft sills, of a coupler, a horizontal yoke, a vertical key connecting said yoke and coupler adapted to permit relative movement therebetween, means connected to the draft sills for supporting and guiding said vertical key, and means connected to the forward ends of said center sills, said last named means being arranged to form a front stop for said vertical key upon movement thereof in a forward direction beyond a predetermined position.

14. In a draft rigging, the combination with draft sills, of a coupler, a horizontal yoke, a vertical key connecting said yoke and coupler adapted to permit relative movement therebetween, means connected to and bridging said draft sills for retaining said vertical key in position, and means adjacent said last named means acting as a stop for the vertical coupler key, said last named means being connected to and bridging said draft sills.

15. In a draft rigging, the combination

- with center sills, of a coupler, a horizontal yoke, means connecting said yoke and coupler, said means including a vertical key adapted to permit relative movement between said yoke and coupler, means connected to said center sills for retaining and guiding the vertical key, said last named means also acting to support and guide the said horizontal yoke.
16. In a draft rigging, the combination with center sills, of a coupler, a horizontal yoke, a vertical key connecting said coupler and yoke and adapted to permit relative movement therebetween, and means including a member connected to the lower portion of said center sills for retaining and guiding said key, said means also acting to support and guide said horizontal yoke.
17. In a draft rigging, the combination with center sills, of a coupler, a horizontal yoke, a vertical key connecting said yoke and coupler adapted to permit relative movement therebetween, means including spaced upper and lower members connected to the draft sills, said members being cooperatively associated with the upper and lower ends of said vertical key for retaining and guiding the same, and means closing the forward end of the draft rigging pocket, said last named means co-acting with said guide members and adapted to form a front stop for the vertical coupler key.
18. In a draft rigging, the combination with a cushioning mechanism, of a key connected follower and horizontal yoke, a coupler, a vertically arranged coupler key connecting said coupler and yoke adapted to permit relative movement therebetween, and means provided above and below said key for guiding the same.
19. In a draft rigging, the combination with a cushioning mechanism, of a key connected follower and horizontal yoke, a coupler, a vertically arranged coupler key connecting said coupler and yoke adapted to permit relative movement therebetween, means for retaining said key in position, and means adapted to prevent movement of the key in a forward direction beyond a predetermined position.
20. In a draft rigging, the combination with draft sills of a cushioning mechanism, a key connected follower, a horizontal yoke, a coupler, means including a vertical key connecting said yoke and coupler and adapted to permit relative movement therebetween, and means connected to the draft
- sills for retaining said vertical key in position, said last named means also serving to guide said coupler key.
21. In a draft rigging, the combination with draft sills, of a coupler, a horizontal yoke, a vertically arranged key connecting said coupler and yoke, and means carried by said draft sills for retaining and guiding said key, said means including upper and lower members connected to the draft sills and also adapted to guide said horizontal yoke.
22. In a draft rigging, the combination with draft sills, of a coupler, a horizontal yoke, means connecting said yoke and coupler, said means being adapted to permit relative movement therebetween, and means for guiding said yoke and coupler connecting means, said last named means also acting to support and guide the forward end of said horizontal yoke.
23. In a draft rigging, the combination with draft sills, of a coupler, a horizontal yoke provided at its forward end with shoulders, a vertical key connecting said yoke and coupler adapted to permit relative movement therebetween, and means connected to the draft sills, said means acting to maintain the vertical key in position and co-act with the aforesaid shoulders on said yoke for supporting and guiding the latter.
24. A draft rigging member comprising a unitary striking casting and carry iron support, said member having integral vertical sections connecting the upper and lower portions thereof and provided with a rear face forming a front stop for a vertical coupler key.
25. A draft rigging member involving a one-piece striking casting and carry iron support, said member being formed with a vertical rear wall forming a front stop for a vertical coupler key, and also being provided with a contiguous wall adapted to form a forward stop for the front end of the horizontal yoke.
26. A draft rigging member involving a unitary striking casting and carry iron support, said member being formed with a rear wall with which the forward end of a horizontal yoke engages when the cushioning mechanism of the draft mechanism becomes solid.

In testimony whereof we affix our signatures.
